SHAKER CONVEYER TROUGH

Ernst R. Bergmann, Evergreen Park, Ill., assignor
to Goodman Manufacturing Company, Chi-
cago, Ill., a corporation of Illinois

Application March 20, 1952, Serial No. 18,983

Term of patent 14 years

(Cl. D55—1)

To all whom it may concern:

Be it known that I, Ernst R. Bergmann, a citizen of the United States, residing at 9705 South Avers Avenue, Evergreen Park, State of Illinois, have invented a new, original, and ornamental Design for a Shaker Conveyor Trough, as shown in the accompanying drawings, wherein:

Figure 1 is a fragmentary perspective view of a shaker conveyor trough showing my new design;

Figure 2 is a bottom plan view of the trough shown in Fig. 1;

Figure 3 is an end view of Fig. 2 as seen in the direction of the arrows 3—3;

Figure 4 is a transverse sectional view taken along the line 4—4 of Fig. 2;

Figure 5 is a fragmentary longitudinal sectional view taken approximately along line 5—5 of Fig. 4;

Figure 6 is an enlarged fragmentary top plan view of the trough; and

Figure 7 is an enlarged fragmentary transverse sectional view of the trough taken along line 7—7 of Fig. 6.

The dominant features of the design reside in the portions shown in full lines.

I claim:

The ornamental design for a shaker conveyor trough, as shown and described.

ERNST R. BERGMANN.
